UNITED STATES PATENT OFFICE

92,286

DESIGN FOR A LIGHTING FIXTURE BOWL

Edward L. Bradbury, Port Jervis, N. Y., assignor
to Gillinder Brothers, Inc., Port Jervis, N. Y., a
corporation of New York

Application March 24, 1934, Serial No. 51,166

Term of patent 7 years

To all whom it may concern:

Be it known that I, EDWARD L. BRADBURY, a citizen of the United States of America, and a resident of Port Jervis, in the county of Orange and State of New York, have invented a new, original, and ornamental Design for a Lighting Fixture Bowl, of which the following is a specification, reference being had to the accompanying drawing, forming a part hereof.

In the drawing:

Figure 1 is an elevation of the lighting fixture embodying my invention;

Figure 2 is a bottom plan view of the same with the ornamentation of the lower portion indicated on a portion thereof.

I claim:

The ornamental design for a lighting fixture bowl substantially as shown.

EDWARD L. BRADBURY.
